UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

RADIOSIGNALING SYSTEM.

1,426,944.

Specification of Letters Patent. Patented Aug. 22, 1922.

Application filed September 4, 1917. Serial No. 189,495.

To all whom it may concern:

Be it known that I, ERNST F. W. ALEXANDERSON, a citizen of the United States, residing at Schenectady, in the county of Schenectady, State of New York, have invented 5 certain new and useful Improvements in Radiosignaling Systems, of which the following is a specification.

My present invention relates to radio signaling systems and comprises both transmitting and receiving apparatus for use in such systems.

One of the objects of my invention is to provide a system of multiplex signaling in which a plurality of messages may be transmitted and received simultaneously by the use of a single wave length.

A second object of my invention is to provide a system for transmitting and receiving messages which is arranged in such a way that it will be practically impossible for another station to interfere with the efficient transmission and reception of the desired messages.

Still another object of my invention is to provide a system whereby messages may be transmitted between two stations in such a way that it will not be possible for a third station to receive them.

In attaining the above objects, I employ, for transmitting purposes, a source of continuous radio frequency current, such, for example, as a high frequency alternator, an arc generator or an electron discharge oscillator. I control the current in the antenna which is supplied by this source by means of a magnetic amplifier of the general type described in my prior Patent #1,206,643. By varying the controlling current supplied to the windings of this amplifier at a frequency lower than that of the source of supply, I produce amplitude pulsations of a desired frequency and of substantially sine wave form in the current 40 supplied to the antenna.

If it is merely desired to transmit simultaneously a plurality of different messages, I supply to the controlling windings of the amplifier currents of as many different lower frequencies as the number of messages which it is desired to transmit, these currents being supplied only during the intervals necessary to form the dots and dashes for each message. It will, of course, be apparent that 55 in case several messages are being sent si-

multaneously, the amplitude pulsations produced in the fundamental wave will be the resultant or combination of the amplitude pulsations produced by the several different frequencies employed. In case the 60 low frequency currents are of sine wave form, the resultant amplitude pulsations will be proportional to the sum of the several sine waves employed. In receiving messages sent in this way, an antenna may be 65 employed, which is tuned to the frequency of the source of supply. In conjunction with this antenna, a secondary receiving circuit may be employed for each message, each secondary circuit being tuned to the particular 70 frequency of the amplitude pulsations which are employed for transmitting the message to be received in that circuit. In this way the resultant wave produced by the combination of the amplitude pulsations of several 75 different frequencies may be resolved into its original low frequency components.

In case it is desired to transmit a message without interference from a foreign station, the message may be transmitted simultaneously by means of amplitude pulsations of several different frequencies. The receiving operator may be provided with means for receiving the message at any one of the amplitude pulsation frequencies transmitted. 80 In order to prevent the proper reception of the message under these conditions, it would be necessary for a disturbing station to set up a wave having amplitude pulsations of 85 the same nature as those produced by the transmitting station. This would be practically impossible unless the disturbing station was informed of all of the frequencies employed by the transmitting station.

In case it is desired to transmit messages 90 in such a way that they can be received only by a desired station, the transmitting apparatus may be so arranged that each message is produced by a succession of amplitude pulsations of different frequencies, 100 coming one after another in a prearranged regular order. In order to receive a message transmitted in this way, it will be necessary that the receiving instrument be connected successively in the same order to circuits tuned to the different frequencies used for producing the amplitude pulsations. It 105 will be evident that it would be practically impossible for a station which was not informed of the different frequencies employed 110

and of the order in which they were used to arrange its receiving apparatus in such a way as to receive a message sent in this way.

The novel features which I believe to be characteristic of my invention are set forth with particularity in the appended claims. The invention itself, however, both as to its organization and method of operation, together with further objects and advantages thereof, will best be understood by reference to the following description taken in connection with the accompanying drawings, in which Fig. 1 is a diagrammatic representation of a transmitting circuit which may be employed for multiplex operation; Fig. 2 shows a receiving circuit for the system shown in Fig. 1; Fig. 3 shows a transmitting circuit which may be used for preventing interference; Fig. 4 shows a receiving circuit for the system shown in Fig. 3; Fig. 5 shows a transmitting circuit which may be used to insure secrecy; and Fig. 6 shows a receiving circuit for the system shown in Fig. 5.

As indicated in Fig. 1, the antenna 1 is supplied with radio frequency current from any convenient source. For the purpose of illustration I have shown it as supplied by the high frequency alternator 2 through the usual transformer 3. The alternator 2 may be driven by a direct current motor 4 mounted upon the same shaft 5 and supplied with current from the mains 6. Connected in shunt to the secondary 7 of transformer 3 is a magnetic amplifier comprising a suitable core 8 of magnetic material and two windings 9 and 10 as indicated. These windings are so arranged that the high frequency current supplied by secondary 7 flows through the two windings 9 and 10 in parallel and that the flux produced by this current flows in opposite directions through the portions 11 and 12 of the core 8.

The current for controlling the magnetic amplifier may conveniently be obtained from a direct current generator 13, mounted upon the same shaft as motor 4 and driven thereby. In order to adjust the magnetization of the core 8 to a point at which the device will operate most efficiently, current may be supplied to the windings 9 and 10 from generator 13 at the points 14 and 15, the strength of this current being regulated by means of the rheostat 16. This current flows through the two windings in series. The points 14 and 15 are at the same potential with respect to the high frequency source and hence, there is no tendency for high frequency current to flow through the circuit which supplies direct current to the windings 9 and 10. The condensers 17 and 18, which are in series with each of the windings 9 and 10, prevent the short circuiting of the direct current circuit.

The arrangement thus far described will

supply to the antenna continuous radio frequency current of a definite constant amplitude. In order to vary the amplitude of the antenna current, it is only necessary to vary the controlling current in windings 9 and 10, which is supplied from the generator 13. In order to vary this current in the manner necessary to produce the desired amplitude pulsations in the antenna current, a series of alternators may be included in a series of circuits shunting the rheostat 16 and generator 13. I have indicated in the present case one convenient way of producing the amplitude pulsations for transmitting simultaneously three different messages. Upon the same shaft 5 which carries the alternator 2 and the motor 4, there may be mounted three alternators 19, 20, and 21. Poles 22, 23 and 24 of these alternators are connected directly to the circuit which supplies direct current to the windings 9 and 10, and poles 25, 26 and 27 are connected to that circuit through keys 28, 29 and 30 respectively. The alternators 19, 20 and 21 are designed to produce currents of three different frequencies lower than that of alternator 2, all of which may if desired be within the range of audibility, for example, alternator 19 may give 800 cycles, alternator 20, 700 cycles and alternator 22, 600 cycles. In such a case, when key 28 is closed 800 cycle current will be supplied to the windings 9 and 10 and the message transmitted by key 28 will be transmitted by means of amplitude pulsations having a frequency of 800. Simultaneously a second message may be transmitted by key 29 by means of amplitude pulsations having a frequency of 700, and a third message may be transmitted by key 30 by means of amplitude pulsations having a frequency of 600. The currents supplied by the alternators 19, 20 and 21 should preferably be of sine wave form in order that the amplitude pulsations produced may be of a harmonic nature.

The system which I have described will preferably be so adjusted that when none of the keys are depressed, about half of the current from the antenna will flow through the windings 9 and 10, and the amplitude of the current flowing in the antenna will be about half of the maximum. When one or more keys are depressed, the controlling current varies and the radio frequency current in windings 9 and 10 will vary accordingly. As a result, there will be a corresponding variation in the antenna current between a maximum and minimum. If the current supplied by the keys is a sine wave alternating current, the effect will be to produce sine wave pulsations in the amplitude of the current in the antenna. The operation of the control apparatus may be improved by the use of a condenser 31, so adjusted that the circuit which includes this condenser and the windings 9 and 10 becomes resonant

when the antenna current is a minimum. It will, of course, be apparent that the same effect may be secured by supplying through the keys 28, 29 and 30 pulsating unidirectional currents of three different frequencies.

In Fig. 2 I have indicated a simple form of receiving system which may be used for receiving upon a single antenna all of the messages transmitted by means of the system shown in Fig. 1. The wave having amplitude pulsations may be received upon the antenna 34, which is tuned to the frequency of the source 2. The received waves are impressed upon the resonant grid circuit of the electron discharge amplifier 35 in the usual manner, as indicated. In the plate circuit of this amplifier I include three tone traps for selecting the three different frequencies of amplitude pulsations which are transmitted. These tone traps comprise the inductances 37, 38 and 39 shunted by the tuning condensers 40, 41 and 42. The inductance 37 and condenser 40 may be tuned to a frequency of 800 cycles; inductance 38 and condenser 41 to a frequency of 700 cycles; and inductance 39 and condenser 42 to a frequency of 600 cycles in case the amplitude pulsations of the different messages correspond to these frequencies. In order to obtain a high degree of selectivity between the different messages, it may be desirable to couple closely to these tone traps other tuned circuits comprising the inductances 43, 44 and 45 and tuning condensers 46, 47 and 48. The coupling may be made through condensers 49, 50 and 51 and receivers, 52, 53 and 54 connected as indicated, may be employed to receive the different messages. With this arrangement as long as the amplitude pulsations are of substantially sine wave form all confusion between the different messages may be entirely avoided.

While I have described a receiving system in which all of the messages are received at a single point, it will be apparent that any one of the messages alone may be received at any point desired, and separate messages may be sent from a transmitting station to as many different receiving stations as desired, all by the use of a single wave length. If the received signal is to be rendered audible the frequency employed for the amplitude pulsations will preferably be within the range of audio frequencies, and since the necessary difference between any two of the frequencies employed may be even less than the 100 cycles which is given in the above example, it is apparent that a large number of different messages may be transmitted simultaneously by a single wave length. In case it is desired to employ a receiver in which the signal gives a visible indication, frequencies lower than audio frequencies may be employed for producing amplitude pulsations. It will also be

apparent that amplitude pulsations of ultra audible frequencies may also be utilized if desired.

The system which I have described may also be conveniently modified for efficient transmission of messages to different stations located at different distances from the transmitting station. In such a case, the messages for the nearer station or stations may be transmitted by amplitude pulsations of a small amount, while the messages for the more distant stations may be transmitted by amplitude pulsations of greater magnitude. This effect may be obtained by the use of variable resistances 55, 56 and 57 in series with the keys 28, 29 and 30 whereby the current flowing through each key may be adjusted independently of the others.

In Fig. 3 I have indicated an arrangement which is especially adapted for preventing interference with the reception of messages by a foreign station.

In this case a single key 55 is substituted for the three keys of Fig. 1 so that when this key is operated, amplitude pulsations of three different frequencies are produced in the antenna current. The message transmitted may be received by turning the receiving apparatus to any one of the amplitude pulsation frequencies employed for transmission. In case a foreign station sends out a disturbing wave which prevents the operator from receiving the message at one frequency, he may change over to another frequency for receiving, and unless the disturbing station was informed of all of the different frequencies employed for producing amplitude pulsations, it would be practically impossible for it to send out a wave which would interfere with reception at all of the different frequencies employed. In Fig. 4 I have indicated a convenient arrangement for receiving, in which a single receiver 56 is employed and a switch 57 is provided, whereby the receiving operator can quickly change from one receiving circuit to another.

In Fig. 5 I have indicated a transmitting system which is especially adapted for sending messages in such a way that they can be received only by a desired station. In this case each message, instead of being transmitted by means of amplitude pulsations of a definite frequency, is transmitted by means of amplitude pulsations of different frequencies coming one after another in a pre-arranged regular order. In order to secure this result, the brushes 25, 26, and 27 may be connected by means of brushes 58, 59, and 60, to three slip rings 61, 62 and 63 respectively. All of these rings are arranged to rotate together and each ring is connected to a segment of a fourth ring made up of three segments insulated from each other. Brushes 65, 66 and 67, which are connected

respectively to keys 28, 29 and 30 are arranged to bear upon ring 64 at equal intervals, so that at any given instant there will be a brush upon each segment, and in no case will there be two brushes bearing upon the same segment. These rings may be made to revolve together in any way desired and at a suitable uniform speed. It will be evident that with this arrangement, the 10 pressing of key 28, for example, to transmit a message will produce in the antenna current amplitude pulsations of three different frequencies succeeding each other in regular order and that other messages may simultaneously be transmitted by keys 29 and 30 in a similar manner. In order to receive messages sent in this way it will be necessary to have at the receiving station another set 15 of revolving rings, as indicated in Fig. 6, 68. which are driven in synchronism with the set at the transmitting station. By this means the different receiving circuits may be connected at the proper time to the right receiving instrument for receiving each message. It will be apparent that in order to receive a message which is sent in this way, the receiving operator must know the order in which the different amplitude pulsations succeed each other, the frequency of each set 20 and the speed at which the revolving rings are driven. It would be practically impossible for anyone who was ignorant of these factors to receive any one of the messages transmitted.

35. While in the above description I have set forth certain ways in which a system of transmitting signals by means of amplitude pulsations in continuous radio frequency waves may be employed, I do not wish to be limited to the particular uses described or to the precise circuit connections which I have shown, as it will be apparent that many modifications may be made in the manner of using my invention without departing 40 from the scope thereof, as set forth in the appended claims.

What I claim as new and desire to secure by Letters Patent of the United States, is:—

1. The method of radio signaling which 50 consists in producing a continuous radio frequency current in a radiating system, transmitting a single signal by simultaneously producing amplitude pulsations of sine wave form of a plurality of different

frequencies, all of which are below radio 55 frequency, receiving the wave thus transmitted and producing an indication of the signal transmitted by selecting from the wave thus received any desired one of the different frequencies of amplitude pulsations. 60

2. The combination in a radio signaling system of an antenna, a source of continuous radio frequency current connected thereto and means for simultaneously producing 65 amplitude pulsations in the current in said antenna of a plurality of different frequencies below the radio frequency, and transmitting a single signal thereby which may be received by selecting any one of said amplitude pulsations, and means at a receiving station for receiving the transmitted wave, and selecting therefrom any desired one of the different frequencies of amplitude pulsation. 70

3. The method of controlling the current in an antenna supplied with a source of continuous radio frequency current and having a magnetic amplifier associated therewith, which consists in simultaneously supplying 80 to the windings of said amplifier controlling currents of a plurality of different frequencies, all of which are of a frequency lower than that of the source, and thereby producing amplitude pulsations of a plurality of 85 different frequencies in the current in said antenna and transmitting a single signal thereby which may be received by selecting any desired one of the different frequencies of amplitude pulsations. 90

4. The combination in a system for transmitting radio signals of an antenna, a source of continuous radio frequency current connected thereto, a magnetic amplifier comprising a magnetic core having windings 95 thereon, which are associated with said antenna and supplied with current therefrom, and means for simultaneously supplying to said windings alternating currents of a plurality of different frequencies, all of which are of a frequency lower than that of the source and transmitting a single signal thereby which may be received by selecting any one of the amplitude pulsations. 100

In witness whereof, I have hereunto set 105 my hand this first day of September, 1917.

ERNST F. W. ALEXANDERSON.
